UNITED STATES PATENT OFFICE.

FRANK P. D'ARCY, OF KALAMAZOO, MICHIGAN.

SPRING STRUCTURE.

1,095,712.

Specification of Letters Patent.

Patented May 5, 1914.

Application filed January 12, 1914. Serial No. 811,575.

To all whom it may concern:

Be it known that I, FRANK P. D'ARCY, a citizen of the United States, residing at Kalamazoo, Michigan, have invented certain new and useful Improvements in Spring Structures, of which the following is a specification.

This invention relates to improvements in spring structures.

10 The objects of this invention are: First, to provide an improved spring structure in which helical or conical springs are used which can be readily transported in the knockdown and readily and quickly assembled in the supporting frame by inexperienced workmen. Second, to provide an improved spring structure in which the springs are securely and rigidly held in position without the use of separate connecting parts.

20 Further objects, and objects relating to details, and economies of construction and operation will definitely appear from the detailed description to follow.

25 I accomplish the objects of my invention by the devices and means described in the following specification.

The invention is clearly defined and pointed out in the claims.

30 A structure embodying the features of my invention is clearly illustrated in the accompanying drawing forming a part of this specification, in which:

35 Figure I is a perspective view of a structure embodying the features of my invention. Fig. II is a top plan view of the same, the upper part of the spring being broken away. Fig. III is a longitudinal sectional view on the line 3—3 of Fig. II.

40 Fig. IV is a transverse sectional view on the line 4—4 of Fig. II.

In the drawing similar reference characters refer to similar parts throughout the several views and the sectional views are 45 taken looking in the direction of the little arrows at the ends of the section lines.

Considering the numbered parts of the drawing, 1 is a U-shaped supporting bar provided at the edges with the upturned flanges 2.

3 is a slot in the upper part of the U-shaped bar which is provided with the lip 4 over-hanging the slot.

5, 5 are openings in the sides of the U-shaped bar through which the end 7 of the conical springs 6 passes. The end 7 of the

spring is slightly offset downwardly and laterally and engages the inner side of a flange 2 so as to prevent its movement in either direction when secured in place. The 60 distance between the openings 5 and the slot 3 is about equal to the diameter of the coil, but the overhanging lip 4 extends toward the openings 5 so that the coil must be compressed to pass this lip and allow the coil 65 to seat itself in the bottom of the slot 3. To secure the spring to the supporting bar, the end 7 is passed through the openings 5 until it comes into engagement with the flange 2. The coil 6 is then compressed until 70 it passes the lip 4 and is pressed into place in the bottom of the slot 3. This holds the spring rigidly and securely to the supporting bar, inasmuch as the lip 4 prevents the spring from rising and a lateral or twisted 75 movement is prevented by the offset end 7 engaging the flange 2.

It will be seen that I have secured a very strong and rigid connection for the springs, and also a structure which can be easily put 80 together by inexperienced workmen without the use of tools or other mechanical devices. Furthermore the openings and slot in the supporting bar, which are provided in this structure, can be very cheaply and easily 85 produced by means of a punch.

I am aware that the particular embodiment which I have here shown is susceptible of considerable variation without departing from the spirit of my invention, and, therefore, I do not wish to be restricted to the same. However, I have found that this form is to be preferred and I desire to claim the same specifically as well as broadly as indicated by the appended claims.

Having thus described my invention, what I claim as new and desire to secure by Letters Patent is:

1. In a spring structure, the combination of a U-shaped supporting bar provided with upturned flanges at the edges thereof, a conical spring having the extreme lower end thereof bent downwardly, a pair of openings in the sides of said U-shaped bar through which the end of said spring passes, a slot in 100 said bar and a lip overhanging said slot, the edge of the bottom coil of said spring being seated in said slot under tension beneath said overhanging lip.

2. In a spring structure, the combination 110 of a U-shaped supporting bar provided with upturned flanges at the edges thereof, a

conical spring, a pair of openings in the sides of said U-shaped bar through which the end of said spring passes, a slot in said bar and a lip overhanging said slot, the edge 5 of the bottom coil of said spring being seated in said slot under tension beneath said overhanging lip.

3. In a structure of the class described, the combination with a U-shaped supporting bar, 10 of a conical spring having the lower end thereof bent downwardly, a pair of openings in the sides of said U-shaped bar, through which the end of said spring passes, a slot in said bar and a lip overhanging said slot, the 15 edge of the bottom coil of said spring being seated in said slot under tension beneath said overhanging lip.

4. In a structure of the class described, the combination with a U-shaped supporting 20 bar, of a conical spring, a pair of openings

in the sides of said U-shaped bar through which the end of said spring passes, a slot in said bar and a lip overhanging said slot, the edge of the bottom coil of said spring being seated in said slot under tension beneath 25 said overhanging lip.

5. In a structure of the class described, the combination with a U-shaped supporting bar, of a conical spring, a pair of openings in the sides of said bar through which the end of said spring passes, and a slot in said bar in which the edge of the bottom coil of 30 said spring is seated under tension.

In witness whereof, I have hereunto set my hand and seal in the presence of two 35 witnesses.

FRANK P. D'ARCY. [L.S.]
